UNITED STATES PATENT OFFICE.

EUGENE F. OSBORNE, OF ST. PAUL, MINNESOTA.

STEAM HEAT AND POWER DISTRIBUTING APPARATUS.

SPECIFICATION forming part of Letters Patent No. 266,046, dated October 17, 1882.

Application filed December 19, 1881. Renewed September 14, 1882. (No model.)

To all whom it may concern:

Be it known that I, EUGENE F. OSBORNE, of St. Paul, in the county of Ramsey and State of Minnesota, have invented certain new and useful Improvements in Steam Heat and Power Distributing Apparatus; and I do hereby declare that the following is a full, clear, and exact description thereof, reference being had to the accompanying drawings, and to the letters 10 of reference marked thereon, which form a part of this specification.

This invention relates to systems of steam-distribution for heat and power purposes in cities and towns, and has for its object to provide means in such systems of steam-distribution as return the water of condensation to the generator and as are extended over territory of greatly unequal elevation, whereby the effect of gravity in the water being returned and 15 due to such unequal elevation may be neutralized and a substantially uniform flow of water and pressure may be maintained in the return-pipes. The invention has been made with more direct reference to the system of distribution 20 set forth in Letters Patent of the United States No. 236,247, granted to me January 4, 1881, and it is for greater clearness herein illustrated in connection with the arrangement of pipes shown in said patent. Said invention may, 25 however, be employed in connection with other systems.

In the drawings, Figure 1 is a longitudinal section of the inclosing box containing a steam-supply pipe and a condense-water-return pipe, 30 arranged the latter above the former, as in the aforesaid Letters Patent, with my improvement applied thereto for the purpose of controlling the descent of water in an inclined return-pipe, arrows applied to the pipe indicating 35 the respective directions of the steam and water in the several pipes. Fig. 2 is a plan view of the intersecting mains at the left of Fig. 1. Fig. 3 is a plan view of pipes having my improvement applied thereto for the purpose of controlling the upward flow of water from a 40 low to a higher point through an inclined pipe. Fig. 4 is an end elevation of the apparatus of Fig. 3 viewed in the direction of the arrow *a* in said figure. Fig. 5 is a section of the valve 45 *S* in Fig. 3.

By referring to my above-mentioned Letters Patent it will be seen that the steam-supply

and condense-water-return pipes of the distribution system therein described are arranged in proximity with each other throughout their 55 extent beneath the ground surface, that the water-return pipe is located immediately over the steam-supply pipe, and that the former discharges into a receiving-tank at the boiler house or station. It will also be observed that 60 means are provided therein for maintaining a certain sufficient difference in pressure between the steam-supply and the condense-water-return pipes to insure a proper circulation throughout the entire distribution system. 65 Moderate differences in elevation of different parts or sections of the distribution-pipes will not prevent this effect; but considerable differences may in some situations do so. Thus in the case of a section of the distribution system 70 higher than the receiving-tank the pressure in the return-pipes of said section will be less than that in the tank or main by the amount of gravity due to a water-column in height equal to the difference in elevation, while in 75 the case of a section lower than the tank or main the pressure in the return will be greater than that in the main return-pipe or in the receiving-tank by the amount of gravity due to a water-column of height equal to the difference 80 in elevation. When this difference is slight no material disadvantage is suffered by reason thereof; but when the difference is considerable it will operate to produce objectionable inequalities in the pressure and flow of 85 water in the return-pipe. For the prevention of these objectionable effects the present invention is made; and to this end it consists in the several features of construction and operation hereinafter set forth and claimed. 90

Referring to the drawings, *A* may represent the steam-supply main, and *B* the condense-water-return main of a circulating steam-distribution system. *A'* and *B'* represent lateral or branch steam-supply and water-return pipes 95 connected with the mains *A* and *B*, and leading respectively to and from a section of the city or town considerably higher than the mains *A* and *B*.

*A*² and *B*² represent lateral or branch pipes 100 connected with the mains, and leading respectively to and from a point or territory materially lower than the mains.

D *D* are double-chambered couplings unit-

ing the mains and branches, the upper chamber furnishing the connection for the pipes B, B', and B², and the lower chamber similarly affording connection for the steam-pipes A, A', 5 and A². The interior construction of said couplings is not shown herein, but for the purposes of this description is sufficiently described by saying that a horizontal diaphragm or partition separates the water-passage from the 10 steam-passage through the same.

For the purposes of this description the mains A and B, at the point where they are shown in section at the left in Fig. 1, may be understood as being substantially at the level of the 15 receiving-tank at the boiler-station, and the pipe B as being therefore under normal pressure. To first consider the case of the pipe B', Fig. 1, wherein the water descends from a considerably-elevated point or district to the main 20 return B: It is plain that unless means are employed to restrain or control the descent of the water in said pipe B' the more elevated portion of the return-pipe may be drained and filled with steam and the pressure in the main B 25 augmented by an amount equal to the gravity due to the vertical height of the column in the inclined pipe B'. This difficulty is obviated by means of an automatic pressure-regulator valve, E, located in the pipe B' near its junction 30 with the main. The valves e are connected by their stem with the piston e', exposed on the lower side to the pressure in the branch B' above the valve, and on the upper side to the pressure in the main B, augmented 35 by the force of the adjustable spring e². The spring e² is set to resist the gravity of a water-column of height equal to the greater elevation 40 of the return-pipe discharging through B'. The movement of water through the valve E 45 will therefore be governed by the variation of water-pressure on opposite sides of the piston e', and will obviously proceed regularly and wholly as in the case of sections of the return-pipe on the same level.

45 In the case of a section located materially below the level of the mains A and B the gravity of the water will have the opposite effect from that above stated, or, in other words, will tend to drain the main return B into the 50 lower branch return, B², and will augment the pressure in such branch. For the purpose of equalizing the pressure and flow between said branch and the main B in this case an automatic steam-pump is employed, being located 55 at a low point, but not at the extremity, and usually not at the lowest point of the branch B², and actuated by the steam taken from the adjacent steam-supply pipe A². Adequate devices for this purpose are shown in Figs. 3 and 60 4, in which S is a direct-acting steam-pump, having its steam-cylinder S' connected with the steam-supply pipe A² and its water-cylinder W with the return-pipe B².

In order to obtain a working steam-head, a 65 differential reducing-valve, E', is inserted in the steam-pipe B², above or on the high-pressure side of which the pipe s leads from the

steam-chamber of the coupling D to the valve-chamber S² of the engine steam-cylinder, and below or on the low-pressure side of which the 70 exhaust s' from said cylinder connects. The pipe s has, in addition to the main valve S³, an automatic pressure-regulator valve, S⁴, (shown in section in Fig. 5,) having its piston 75 s³ exposed on its lower face to the steam-pressure, and its upper face exposed to the pressure of water from the water-chamber of the coupling D. The valves s⁵ are arranged to open by excess of pressure on the upper face of the valve, where the expanding-spring s¹ is located, 80 to augment the pressure of the water. On the side toward the ascending return-pipe B² this pipe is cut off from the coupling D by a cap or plug, P, as shown, or by a stop-valve. The water-cylinder W of the pump takes its supply through the pipe w, connected into the water-chamber of the coupling D, and discharges into the pipe B² by the pipe w', connected with said pipe above or beyond the point of severance, as shown. The entire body 85 of condense-water will therefore be passed through the pump-cylinder W. The relative diameters of the steam and water cylinders are determined with reference to the elevation to which the water is to be raised against the 90 pressure in the main return B, and with reference to the steam-head available and provided by the differential valve E'. The valve S⁴ is adjusted to open when the pressure in the water-chamber of the coupling D is above 95 normal, and to thereby operate the pump for the delivery of the water against the pressure from the elevation, as stated.

If preferred, a rotary engine and pump may be arranged directly in the respective pipes 105 A² and B², the propelling mechanism in the steam-pipe and the pump in the water-pipe both being connected by the same shaft and controlled by a suitable valve.

The same means here shown may of course 110 be applied to the mains themselves when the same extend to sections of a city of unequal elevation.

I claim as my invention—

1. In a circulating steam-supply system returning the water of condensation to the generator and extending to districts of unequal elevation, the combination, with the condense-water-return pipe, of automatic mechanism, substantially as described, for controlling the 115 flow of water therein in opposition to the force of gravity due to the difference in elevation, substantially as set forth.

2. In combination with a pipe giving descent to the water of condensation in a steam-supply circulation, the pressure-regulator valve 125 E, arranged in said pipe near the point of normal pressure, substantially as and for the purpose specified.

3. In combination with a condense-water-return pipe giving ascent to the water of condensation in a steam-supply circulation, and with an adjacent steam-supply pipe, a pump 130 automatically operated by steam from said sup-

ply and connected to force the water upward in the return-pipe, substantially as set forth.

4. In combination with the steam-supply pipe having a reducing-valve, E', and the adjacent condense-water-return pipe, disconnected at P at a low point thereof, a steam-pump, S, having its steam-supply ^s, provided with an automatic valve, S⁴, connected to open by the pressure of water in the return-pipe below the point of disconnection, and its steam-exhaust connected into the steam-supply pipe beyond the valve E', and having its water-cylinder

connected to receive from the return-pipe below and to deliver into the same above its point of disconnection, substantially as described, and for the purposes set forth. 15

In testimony that I claim the foregoing as my invention I affix my signature in presence of two witnesses.

EUGENE F. OSBORNE.
